UNITED STATES PATENT OFFICE.

JONATHAN M. STEWART, OF CANTON, OHIO.

DESIGN FOR A CLOTHES-LINE-CLAMP FRAME.

SPECIFICATION forming part of Design No. 31,186, dated July 11, 1899.

Application filed June 9, 1899. Serial No. 719,968. Term of patent 7 years.

To all whom it may concern:

Be it known that I, JONATHAN M. STEWART, a citizen of the United States, and a resident of Canton, Stark county, Ohio, have invented and produced a new and original Design for a Clothes-Line-Clamp Frame, of which the following is a specification, reference being had to the accompanying drawings, forming part thereof.

- Figure 1 is a perspective view. Fig. 2 is a similar view showing the device in a different position. Fig. 3 is a transverse section on line xx , Fig. 2.

As shown in the drawings, the leading or material feature of my design consists of a straight plate or bar 1, having at its bottom or lower end the right-angled portion or extension 2, the top or upper side of which extension is convexed, as illustrated in the drawings, and at the outer end of said right-angled portion 2 is located the upward and outward curved flange or plate 3, said curved plate being tapered toward its upper end and terminating at the point 4. Upon the outer 5 side of the plate 1 and the under side of the

right-angled portion 2 is located the flange 5, which flange extends upward beyond the top of plate 1 and is continued to form the bar 6, the upper end of said bar being formed of sufficient width to engage with the plate 1. 30 The bottom or lower portion of the bar 6 is provided with the right-angled portion 7, said right-angled portion being located about midway between the shoulder 8 and the convexed top of the right-angled portion 2. A short 35 distance above the shoulder 8 and in the wide portion of the bar 6 is formed the aperture or opening 9.

Having described my invention, what I claim as new, and desire to secure by Letters 40 Patent, is—

The design for a clothes-line-clamp frame, as herein shown and described.

In testimony that I claim the above I have hereunto subscribed my name in the presence 45 of two witnesses.

JONATHAN M. STEWART.
